DESIGN FOR A SAMPLE CASE FOR PISTON RINGS OR THE LIKE

Robert E. Ripley, St. Louis, Mo.

Application April 17, 1941, Serial No. 100,468

Term of patent 7 years

To all whom it may concern:

Be it known that I, Robert E. Ripley, a citizen of the United States, residing at the city of St. Louis, in the State of Missouri, have invented a new, original, and ornamental Design for a Sample Case for Piston Rings or the like, of which the following is a specification, reference being had to the accompanying drawing, forming part thereof.

In the drawing,

Fig. 1 is a side elevational view of a sample case for piston rings or the like in closed position showing my new design.

Figs. 2 and 3 are opposite end elevational views thereof;

Fig. 4 is a plan view on an enlarged scale of a sample case in open position, showing my new design; and

Fig. 5 is a sectional view thereof on the line 5—5 of Fig. 4.

I claim:

The ornamental design for a sample case for piston rings or the like, as shown.

ROBERT E. RIPPLEY.
